UNITED STATES PATENT OFFICE

94,020

DESIGN FOR AN ALPHABET FOR FORMING MONOGRAMS OR THE LIKE

Michael Chernow, Brooklyn, N. Y.

Application February 27, 1934, Serial No. 50,890

Term of patent 7 years

To all whom it may concern:

Be it known that I, Michael Chernow, a citizen of the United States and residing at Brooklyn, in the county of Kings and State of New York, have invented a new, original, and ornamental Design for an Alphabet for Forming Monograms or the like, of which the following is a specification, reference being had to the accompanying drawing, forming part hereof, and in which

The figure is a view of an alphabet showing my new design.

I claim:—

The ornamental design for an alphabet for forming monograms or the like, substantially as shown.

MICHAEL CHERNOW.
